HEEL CLAMP

William H. Poindexter, St. Louis, Mo.

Application January 22, 1934, Serial No. 707,673

8 Claims. (Cl. 12—125)

This invention relates to certain new and useful improvements in heel clamps, the peculiarities of which will be hereinafter fully described and claimed.

The main objects of my invention are to provide means first, for clamping a heel firmly to the shoe while the interposed cement is setting; second, for locking the clamp in position; third, for providing a self-contained clamp which continues its hold upon the heel independently of any machine, and thus allows of handling the shoe and clamp as a unit in further operations on the shoe till it is desired to remove the clamp; fourth, for speeding up the finishing operations on shoes by the use of my device in multiple on multiple shoes being finished; and other objects hereinafter described and claimed.

In the accompanying drawing in which like reference numerals indicate corresponding parts, Fig. 1 represents a side view of my device, partly broken away, as applied to a heel and shoe indicated by dash lines;

Fig. 2, a top plan view of Fig. 1; and
Fig. 3, a reversed plan of the bottom of Fig. 1.

When heels are cemented or otherwise fastened to shoes, it is necessary to clamp them in position while the cement sets or other fastening is effected. Furthermore, succeeding operations on the shoe that require its removal from the machine, are delayed by the machines now in use till the heel is firmly secured on the shoe.

My heel clamp applied to the shoe by hand or otherwise, and locked on the shoe, holds firmly together the heel and shoe and interposed cement; and immediately upon such clamping attachment, will allow of handling the shoe and my clamp as a unit (unconnected with any machine,) while succeeding finishing operations are performed. Thus with my device it is not necessary to wait (as is customary,) for the cement between the heel and shoe to set and secure the heel in position. Also, a multiple number of my heel clamps can be used on multiple shoes in the course of being finished, and thus speed up shoe production with corresponding reduction of cost.

Referring to the drawing, the numeral 1 designates a square upright piece or post, having an L-shaped offset at its lower end forming a rounded end 2 with a hole in which is slidably mounted a vertical stem 3 having a top 4, preferably recessed or otherwise adapted to support a last contained in a shoe, as indicated by dash lines in Fig. 1. A stiff coil spring 5 mounted on said stem between the offset end 2 and said top, is controlled by a nut 6 threaded on the stem below

the end 2, and forms an adjustable stop for the upward tendency of the spring. A spring base to support the shoe yieldably is thus provided.

The stem and its top are rotatable and the bottom of the recess 7 (Figs. 1 and 2,) is formed with intercepting surfaces inclined to each other to suitably engage heels that are cut under more or less.

On the post 1 is slidably mounted a horizontally projecting arm of a presser head 8, offset from the post in front and opposing said spring base so as to clamp an interposed heel, shoe and contained last in their reversed position as indicated in Fig. 1. This head has a deep vertical web 9 bearing against the adjacent front face of the post, and has also a rearward extension consisting of a pair of parallel lugs 10 extending past the sides of the post which they embrace by guide slots having shoulders 11 which engage the rear face of the post at each side of gripping means in the form of ratchet teeth 12 pointing downward. The head is thus guided in its sliding adjustment on the post.

Between the rear ends of these parallel lugs is located a pivot pin 13 on which is mounted a clamping lever consisting of a rotatable cam having a lifting tooth 14 formed by a radial notch 15 and a depending quadrant 16 of increasing radius expanding downward from the tooth. A lever handle 17 rotates the toothed cam and turns the longer radius of the lower portion of the quadrant closer to the post when the handle is thrown forward to the dash position, Fig. 1. This cam rotation thus exerts a lifting movement by said tooth from its horizontal position shown in Fig. 1, and a horizontally pressing movement by the quadrant portion, upon an operative connection.

Such operative connection is formed by a dog 18 consisting of a straight leg 19 disposed parallel to the post between said cam and post. On the front face of said leg are gripping means formed by ratchet teeth 19 pointed upward and adapted to grip the opposing teeth 12 on the post. On the opposite rear side of said leg is a curved notch 20 forming an overhanging shoulder 21, normally engaged by the upper face of said tooth 14 as shown in Fig. 1.

Throwing the lever handle 17 as indicated, lifts the dog and post together relatively to the presser head and brings the lower end 2 of the post nearer the head. This compressive movement exerts a strong spring pressure on the heel, shoe and last thus clamped between the presser head and the top 4, while the expanding quadrant 15

bears on the curved notch below the shoulder and holds the teeth of post and leg intermeshed.

Any suitable means for locking the lever handle in said thrown position to maintain the clamping action while handling the shoe in succeeding finishing operations may be employed, but my preferred means is as follows.

The clamping lever is extended beyond the cam and has a pointed end 22 which engages a 10 rearwardly extending arm 23 of said dog as in Fig. 1. This arm is curved downward to follow the rearward swing of said end, and is preferably provided with a slight notch 24 near its rear end, to receive said end 22 when the handle is thrown 15 forward to the dash position; the downward reaction of the arm 23 is thus transferred to the rear of the pivot and locks the handle close to the post, to facilitate handling as stated.

A slidingly adjustable heel stop is provided by 20 an inclined brace 25 having a curved lower end to engage the heel, and an upper end having branching arms 26 forming a yoke embracing the presser head. The ends of said arms are rectangular and project inward toward each other, 25 and slide in vertical guide slots 27 in the sides of said head. A thumb screw 28, mounted in one of the yoke ends, secures the stop in its properly located adjustment to brace the heel in the desired position on the spring base 4.

30 I claim:

1. A heel clamp of the class described, comprising a post having an offset lower end, a spring base mounted on said end to support a shoe, a presser head slidably mounted on said post and 35 projecting over said base in front and having an extension rearward of said post, a lifting cam mounted in said extension, and operative connecting means interposed between said cam and post, substantially as described.

40 2. A heel clamp of the class described, comprising a post having ratchet teeth pointed downward and having its lower end offset and provided with a spring support for a shoe, an offset presser head slidably mounted on said post over 45 said support and having parallel rearward lugs with guides embracing said post, a pivoted cam with lever handle mounted between said lugs and consisting of a lifting tooth and quadrant, an operative connection between said cam and 50 post consisting of a leg disposed between said cam and post and having ratchet teeth pointed upward to mesh with said post teeth and having a notch forming an overhanging shoulder and bearing surface, and locking means for said cam lever, substantially as described.

55 3. A heel clamp of the class described, comprising a post having ratchet teeth on its rear face and having an offset lower end provided with a support for a shoe, a presser head slidably 60 mounted on said post over said support and having an extension rearward of the post, a toothed cam having a lever handle and a pointed upper end pivotally mounted in said extension, an op-

erative connection between said cam and post consisting of a leg having teeth on its front face to engage the post and a notch on its rear face to engage the toothed cam, said leg having a rearwardly extending arm curved downward adjacent said pointed end to engage and lock said lever after lifting said post, substantially as described.

4. In a heel clamp of the class described, the combination with a shoe support, a post, a slide- 10 able head mounted thereon having a rearward extension, and a rotary cam pivoted in said ex- 15 tension having a horizontally disposed tooth and a depending quadrant of increasing radius and having a pointed end and lever handle above and below the cam respectively, of an operative connection between said cam and post consisting of a straight leg having gripping means on its front 20 face and having a notch on its rear face forming a shoulder and a bearing surface to engage said tooth and quadrant respectively, said leg having a rearwardly curved arm adjacent said pointed end to engage and lock the lever handle in its forward position, substantially as described.

5. In a heel clamp of the class described, the 25 herein described clamping lever consisting of a pivoted rotary cam having a horizontally dis- 30 posed tooth and a depending quadrant, and hav- 35 ing a pointed end above the cam and a lever handle below the cam, in combination with a shoe support, a pivotal support for said lever, and cooperative parts engaged by said tooth and quadrant and pointed end, substantially as de- 40 scribed.

6. In a heel clamp of the class described, the 35 herein described sliding heel brace consisting of an inclined brace having spreading arms forming a yoke having rectangular opposing inner 40 ends, and a thumb screw in one of said ends, in combination with a shoe support, and a slideable 45 presser head having guiding slots on its opposite faces for said yoke ends, substantially as de- 50 scribed.

7. In a heel clamp of the class described, the 45 herein described presser head consisting of a front projecting arm with a bracing web and rearward parallel lugs having guiding shoulders opposite said web, in combination with a shoe 55 support, a post mounted between said web and shoulders, and means to move said post relatively to said head, substantially as described.

8. In a heel clamp of the class described, the 55 herein described support for a shoe on a last, comprising a stem having a non-tipping top pro- 60 vided with a recess having multiple inclinations on its bottom forming a surface of varied inclina- 65 tion to support a last carrying a shoe, in combi- 70 nation with a vertically adjustable presser head, a post operatively connecting said support and head, and means to vary the position of said head and post relatively to each other.

WILLIAM H. POINDEXTER.
